UNITED STATES PATENT OFFICE

LOUIS A. M. PHELAN, OF ELKHART, INDIANA, ASSIGNEE, BY MESNE ASSIGNMENTS, TO
TIME-O-STAT CONTROLS COMPANY, OF ELKHART, INDIANA, A CORPORATION OF
MARYLAND

ELECTRIC SWITCH

Application filed December 22, 1926. Serial No. 156,341.

This invention relates to electric switches and it has special reference to improvements in electrical contact-making devices which comprise a container for enclosing a pair of electrodes or conducting terminals and a compact and coherent body of current-conducting fluid through the agency of which fluid said electrodes are brought into electrical conducting relation with one another.

10 One of the objects of this invention is to provide a device of the character indicated, which is capable of reducing to a minimum the amount of current-conducting fluid necessary within the container to bring the electrodes into electrical conducting relation one with another.

Further objects of this invention will be apparent from the description and drawings forming a part of this specification, to 20 which reference may now be had for a more complete understanding of the characteristic features of this invention.

In the drawings:

Figure 1 is a sectional view of a preferred 25 embodiment of this invention;

Fig. 2 is a view similar to Fig. 1, showing the device actuated into an extreme position for test purposes.

Fig. 3 is a sectional view of a further embodiment of this invention; and

Fig. 4 is a sectional view taken on the line 4—4 of Fig. 3.

Referring to the drawings and particularly to Figures 1 and 2, the switch or contactor comprises a container 1 in which two spaced electrodes 2 and 3 are hermetically sealed. The electrodes 2 and 3 are shown as being disposed in spaced relation to each other adjacent one end of the container, and 35 fixed to supporting members 4 and 5. The supporting members are, in turn, connected to leading-in wires 6 and 7, respectively, which provide means for electrically connecting the electrodes 2 and 3 to their respective 40 accessible terminals 8 and 9. A body of mercury 10 is also disposed within the container 1 and serves to bridge the electrodes 2 and 3, thus establishing an electric circuit 45 through the contactor.

50 The container may, if desired, be made of

glass of the quality usually employed in manufacturing incandescent lamp bulbs, etc. When the container is so made, the leading-in wires 6 and 7 are preferably made of a suitable wire in order to insure the retention 55 of permanent hermetic seals for the container, for instance when the seals become heated, or, when substantially high currents are handled by the contactor. A very well known form of sealing-in wire for the above 60 mentioned glass container is known in the trade as "Dumet", which consists of an exterior copper coating over a core of nickel-iron alloy. In order to prevent exposure of the leading-in wires situated in the interior of the container, glass shanks 11 and 12 are provided, in which said leading-in 65 wires are embedded.

On the other hand, said container 1 may also be made of pyrex, or, if desired, of boro-silicate glass. If this type of glass be used, the leading-in wires are preferably made of tungsten, which latter has been found very satisfactory as a sealing-in wire in connection with pyrex and the like.

The supporting members 4 and 5 for the electrodes are connected to their respective leading-in wires 6 and 7 by means of welding, or any other desirable method, and said connections are then embedded in their 75 respective glass shanks.

The supporting members 4 and 5 in either of the instances mentioned may be made of a non-deteriorating or inert material, such as iron. The electrodes 2 and 3 are likewise 85 made of iron, or of some allied product of iron, as iron-chromium alloy containing approximately 18% chromium, which has been found to be satisfactory.

In order to maintain the interior of the 90 container 1 inert to the materials entering into the construction of the device, the atmospheric air is evacuated from the container to a substantially high degree, and the container is then filled with an inert 95 gas, such as hydrogen, to a pressure preferably approximating atmospheric pressure. By this means of filling the container with an inert gas, and further, by properly selecting the materials exposed within the inter- 100

rior of the container, deterioration and disintegration of the contactor are greatly reduced when said contactor is subjected to severe service conditions.

5 The body of mercury 10 disposed in the container to bridge the electrodes 2 and 3 should be chemically pure. Also, in order to increase the mobility of the mercury to effect a rapid flow back and forth in the container, a small quantity of a solution of hydrocyanic acid, or other compounds of cyanide, may, if desired, be mixed with the mercury. In the operation of the switch, the contactor is tilted slightly in one direction 10 causing the mercury to flow in the same direction and thus bridge the electrodes 2 and 3, which action establishes an electric circuit through the contactor. In like manner a tilting of the contactor in the opposite direction past a horizontal position will cause the mercury to flow in that direction and break the circuit.

In order to reduce to a minimum the amount of mercury to be used in the container 1, the 25 electrodes 2 and 3 may be disposed substantially at right angles to each other and adjacent one end of the container near the bottom thereof. The end of the container in which these electrodes are disposed has a reduced 30 portion 13 provided preferably by an inclined surface 14 extending from the top of the container to the lower rounded portion thereof. As illustrated by Fig. 2 of the drawings, the test by which the amount of 35 mercury is determined in the container irrespective of the position of the container, resides in placing the container on end and noting that the mercury bridges the electrodes.

It is obvious that by reducing the size of 40 the end portion and by properly positioning the electrodes therein, a minimum of mercury is required to effectively bridge the electrodes.

The container in a device of this character may be made in various shapes to accommodate 45 any desired positioning of the electrodes, however, said container is here shown with a reduced end in an endeavor to illustrate a simple type of construction, but it will be apparent, of course, to those skilled in the art, 50 that such a container could readily and conveniently be produced in a variety of shapes and modifications for embodying the broad features of this invention.

A further embodiment of this invention is 55 illustrated in Figs. 3 and 4 wherein the container 15 is of ordinary shape and size in which is disposed a pair of electrodes 16 and 17 and fixed to the supporting members 18 and 19. The supporting members are in turn 60 connected to leading-in wires 20 and 21, said connections being made in glass shanks 22 and 23 in which the leading-in wires are embedded. A body of mercury 24 is disposed 65 within the container 15 and serves to bridge

the electrodes 16 and 17 and thereby establishes a circuit through the contactor.

In the above mentioned embodiment, the electrode 16 is shown as being substantially disc shaped with its outer surface of a contour substantially like that of the rounded end of the tube. The electrode 16 is also of a size considerably larger than that of the electrode 17 and occupies a substantial portion of the end of the container in which it is disposed. When tilted on end to determine the amount of mercury necessary by the extreme position of the container, the mercury will assume a position as shown by the dotted line 25. It will be apparent that by providing an electrode 17 of the character described and which occupies the greater portion of one end of the container, a minimum amount of mercury will be required to bridge the electrodes.

While but two specific embodiments of this invention are herein shown and described, it is to be understood that this invention is not to be limited to these structures, since various modifications will be apparent to those skilled in the art without departing from the spirit and scope of this invention, and the same is, therefore, to be limited only by the scope of the appended claims and the prior art.

I claim:

1. An electrical contactor comprising a sealed container having a reduced portion, electrodes sealed within said container, a compact and coherent body of electrical conducting fluid within said container and adapted to bridge said electrodes when in one position, said electrodes being positioned adjacent said reduced portion, said reduced portion being provided by an inclined surface extending from the top of said container to a lower rounded portion thereof, and said electrodes being positioned adjacent said inclined surface and within said lower rounded portion to reduce to a minimum the amount of said electrical conducting fluid required.

2. An electrical contactor comprising a sealed container having a reduced portion, electrodes sealed within said container, a compact and coherent body of electrical conducting fluid within said container and adapted to bridge said electrodes when in one position, said electrodes being positioned adjacent said reduced portion, said reduced portion being provided with an inclined surface extending from the top of said container to a lower rounded portion thereof, and one of said electrodes being positioned adjacent said inclined surface and within said lower rounded portion to reduce to a minimum the amount of said electrical conducting fluid required.

3. An electrical contactor comprising a sealed container having a rounded end, elec-

- trodes sealed within said container, and a compact and coherent body of electrical conducting fluid within said container, one of said electrodes being enlarged and substantially disc shaped and having a surface of a like contour with that of the rounded end of said container, said latter electrode to occupy a substantial portion of said rounded end to reduce to a minimum the amount of said electrical conducting fluid required. 10
4. An electrical switch comprising an elongated cylindrically-shaped container that is adapted to be tilted to circuit opening and circuit closing positions by tilting about a centrally disposed horizontal transverse axis, said container having a portion thereof provided with a reduced cross sectional area, enlarged headed electrodes sealed within said container, and a compact and coherent body of electrical conducting fluid in said container and adapted to bridge the electrodes when the container is tilted, the ends of said electrodes being spaced from each other longitudinally of said container and in proximity to the end portion of said container and the enlarged head of at least one of said electrodes being disposed in said portion of the container having the reduced cross-sectional area. 25
5. An electrical contactor comprising a sealed elongated cylindrically-shaped container that is adapted to be tilted to circuit opening and circuit closing positions by rotating about a centrally disposed horizontal transverse axis, said container having a deformed portion to reduce thereat its cross sectional area, electrodes sealed within said container, and a body of conducting fluid within said container for bridging said electrodes when the container is tilted in one direction about its tilting axis, said electrodes being spaced from each other longitudinally of said container and occupying positions within said deformed portion thereof to reduce to a minimum the amount of conducting fluid required to bridge said electrodes. 30
6. An electrical contactor comprising a sealed elongated cylindrically-shaped container that is adapted to be tilted to circuit opening and circuit closing positions by rotating about a centrally disposed horizontal transverse axis, said container having a deformed portion to reduce thereat its cross sectional area, electrodes sealed within said container, and a body of conducting fluid within said container for bridging said electrodes when the container is tilted in one direction about its tilting axis, said electrodes being provided with enlarged heads that are spaced from each other longitudinally of said container and at least one of said enlarged heads being positioned within said deformed portion to minimize the amount of conducting fluid required to bridge said electrodes. 35
7. An electrical contactor comprising a sealed elongated cylindrically-shaped container that is adapted to be tilted to circuit opening and circuit closing positions by rotating about a centrally disposed horizontal transverse axis, said container having a deformed portion to reduce thereat its cross sectional area, electrodes sealed within said container, and a body of conducting fluid within said container for bridging said electrodes when the container is tilted in one direction about its tilting axis, said electrodes having enlarged heads that are spaced from each other longitudinally of said container and which occupy a substantial portion of said reduced portion of said container to minimize the quantity of conducting fluid required to bridge said electrodes. 40
- In witness whereof, I have hereunto subscribed my name. 45
